United States Patent Office

Des. 180,241
Patented May 7, 1957

180,241

CAN OPENER

Ralph I. Meader, Takoma Park, Md.

Application September 6, 1955, Serial No. 37,797

Term of patent 3½ years

(Cl. D22—2)

Fig. 1 is a perspective view of a can opener showing my new design;

Fig. 2 is a top plan view;

Fig. 3 is a front elevational view;

Fig. 4 is a rear elevational view; and

Fig. 5 is a side elevational view.

I claim:

The ornamental design for a can opener, substantially as shown.
